2 Sheets-Sheet 2

UNITED STATES PATENT OFFICE.

EDWARD J. HARDTKE, OF MILWAUKEE, WISCONSIN, ASSIGNOR TO SEAMAN BODY CORPORATION, OF MILWAUKEE, WISCONSIN, A CORPORATION OF WISCONSIN.

DOOR.

Application filed October 30, 1924. Serial No. 746,727.

This invention relates to improvements in doors and more particularly to automobile doors pressed from sheet metal and adapted to support and receive a window frame.

5 Considerable effort has been made to construct an automobile body which can readily be changed from an open body to a closed body or vice versa. For this purpose the side windows of the body have been slidably mounted in suitable guides between the walls thereof in many different ways well known to those skilled in the art, and a suitable crank or other means provided for raising and lowering the windows.

15 There has been some difficulty, however, in providing a door which may be economically manufactured and at the same time have the required strength and rigidity for supporting the window frame and actuating mechanism therefor and to receive the frame so that the same disappears entirely within the door.

20 Many attempts have been made to press doors of this character from sheet metal, but 25 various problems which arise in bending and shaping the metal have resulted in doors which are too expensive to permit of competitive manufacture if the proper strength and rigidity is to be given them to properly support the window frame and actuating mechanism therefor.

30 One of the objects of the present invention, therefore, is to provide an improved door which is pressed from sheet metal and bent to 35 provide reinforcing members and to receive a window frame, and which may be economically manufactured.

40 Another object is to provide an improved door which is pressed from a single sheet of metal and bent in such wise as to provide a door reinforced at its edges and adapted to receive a window frame and support the actuating mechanism therefor.

45 Other objects and advantages will herein-after appear.

For the purpose of illustrating the invention, an embodiment thereof is shown in the drawings, in which

50 Figure 1 is a side elevation, showing the improved door applied to the body of a car and the window raised to make a closed car;

Fig. 2 is a section on line 2—2 of Fig. 1;

Fig. 3 is a section on line 3—3 of Fig. 1.

Fig. 4 is a perspective view, partly broken away, of the improved door, showing the 55 manner in which the edges thereof are bent and shaped; and

Fig. 5 is a detail sectional view showing a modification.

The door comprises, in general, a front panel 1 having the top edge thereof bent rearwardly, as shown in Fig. 3, to provide a reinforcing top plate 2, and a reinforcing member 3 at the bottom edge of the door. The top plate 2 may be bent back upon itself 60 to provide a reinforcing bead 4 at the edge thereof, and then bent downwardly and rearwardly to provide a reinforcing member 5 for the top edge of the door, (member 5 being shaped to form with top plate 2 and 65 the top edge portion of panel 1 a box-shaped or substantially enclosed channel reinforcing member therefor, as shown in Fig. 3). The front edge of panel 1 to which the 70 hinges are applied in mounting the door 75 upon the body is bent rearwardly and inwardly as shown in Figs. 2 and 4 to form a side reinforcing member 6 providing a channel 7 for the purpose hereinafter explained. The rear side edge of panel 1 is 80 bent back upon itself, then rearwardly and inwardly to provide a reinforcing bead 8 and a reinforcing member 9 providing a channel 10 for the purpose hereinafter 85 explained. The top plate 2 terminates short 90 of the inwardly extending portions 11 and 12 of members 6 and 9, respectively, as shown in Fig. 4. The ends of top plate 2 are secured to the portions 13 and 14 of members 6 and 9, respectively, in any suitable manner 95 such as by soldering or spot-welding. The bottom edge of panel 1 may be bent back upon itself to form a reinforcing bead 15, as shown in Fig. 3. The reinforcing member 3 for the bottom edge of the door may be substantially U-shaped, as shown in Fig. 3, this member having the lower edge 16 thereof bent downwardly and pressed between the folds of bead 15. Member 3 thereby provides a box-shaped or substantially enclosed channel reinforcing member 100 with the bottom edge portion of panel 1, to give added strength and rigidity to the bottom edge of the door.

The inwardly extending portions 11 and 12 of the side reinforcing members 6 and 9, 105

respectively, may be flush with the vertical portion 17 of member 3 and secured to the ends thereof, as at 18, in any suitable way. The upper edge of member 3 may be bent upwardly to provide a reinforcing flange 19 therefor. The bead 15 and member 3 may be integral, as shown in Fig. 5. When this is the case, the entire door is formed from a single piece of sheet metal.

19 The upper portion of panel 1 may be pressed outwardly to form longitudinal reinforcing corrugations 20 and 21 to align with similar corrugations 22 and 23, respectively, formed in the body of the vehicle as shown in Fig. 1. When these corrugations are formed, the sheet metal may be cut away at the portions thereof to be corrugated so that there will only be a single layer of the metal at the portions of bead 20 which constitute the ends of corrugations 20 and 21, as shown in Fig. 4, thus facilitating the corrugating operation.

25 Channel guides 24 for the window frame 25 are fitted in channels 10 and 7, the guides being secured to portions 13 and 14 and inwardly extending portions 11 and 12 in any suitable manner such as by soldering or spot-welding. The upper ends 26 and 27 of portions 11 and 12, respectively, may be bent 30 forwardly over the rear flanges of channel guides 24, as shown in Figs. 3 and 4. A suitable wood panel or backing 28 is secured in any suitable way to inwardly extending portions 11 and 12 and vertical portion 17 of 35 member 3, the wooden panel 28 being adapted to support the actuating mechanism for window frame 25, the lock and other accessories which may be applied to the door.

40 The guides 24 for window frame 25 form the subject matter of a separate application filed October 30, 1925, Serial No. 746,726, and are only here shown and described with sufficient clearness to enable those skilled in the art to understand the manner in which they may be applied to doors made in accordance with the present invention.

45 Various changes in the size, shape and arrangement of the parts may be adopted without departing from the spirit of the invention or the scope of the claims.

The invention claimed is:

50 1. A sheet metal door constructed of a single piece of metal having the main portion thereof constituting the front panel of the door, the upper edge portion of the piece of metal extending inwardly from the main portion to provide a reinforcing top plate, the side edge portions of the piece of metal extending inwardly from the main portion and having their extremities extending toward each other and terminating in spaced relation to the main portion to provide reinforcements for the sides of the door.

55 2. A sheet metal door constructed of a

single piece of metal having the main portion thereof constituting the front panel of the door, the upper edge portion of the piece of metal extending inwardly from the main portion to provide a reinforcing top plate, the side edge portions of the piece of metal extending inwardly from the main portions and having their extremities extending toward each other and terminating in spaced relation to the main portion to 70 provide reinforcements for the sides of the door, the lower edge portion of the piece of metal being bent back against the panel and formed to constitute a substantially U-shaped reinforcing member having one leg integral with the front panel and having its other leg located in spaced relation to the front panel, the body portion of the U-shaped reinforcing member being secured to the extremities of the side edge portions. 80 85

3. A sheet metal door having a panel, a reinforcing top plate integral with the upper edge of the panel, reinforcing side members integral with the side edges of the panel and made up of inwardly extending portions having extremities extending toward each other and terminating in spaced relation to the panel, and a reinforcing member connected to the lower edge of the panel and extending upwardly in 90 spaced relation to the panel and secured to the reinforcing side members.

4. A one-piece sheet metal door comprising a front panel having the top edge thereof bent rearwardly to provide a reinforcing top plate for said door, the side edges of said panel being bent rearwardly and inwardly to provide reinforcements for the sides of said door and channels for receiving guides for a window frame, said top 100 plate terminating short of the inwardly bent portions of said side edges, the lower edge of said panel being bent back upon itself to form a bottom rail for the door and a reinforced edge depending from said rail. 110

5. A sheet metal door constructed of a single piece of metal having a main portion thereof constituting the front panel of the door, the upper edge portion of the piece of metal extending inwardly from the main 115 portion to provide a reinforcing top plate and thence downwardly and outwardly below the reinforcing top plate to coat therewith and with the adjacent upper portion of the panel to provide a box-like reinforcement for the upper end of the door, reinforcing members along the sides of the door and a reinforcing member along the lower end of the door.

6. A sheet metal door constructed of a 120 single piece of metal having the main portion thereof constituting the front panel of the door, the upper edge portion of the piece of metal extending inwardly from the main portion to provide a reinforcing top plate, 125 130

the side edge portions of the piece of metal extending inwardly from the main portion and having their extremities extending toward each other and terminating in spaced relation to the main portion to provide reinforcements for the sides of the door, said top plate terminating short of the extremities of the side edge portions and the channels mounted on the door and vertically aligned with the spaces between the edge of the top plate and said extremities.

7. A sheet metal door comprising a front panel having the top edge thereof bent downwardly and rearwardly to form a box-shaped reinforcing member at said edge, the bottom edge of said panel being bent back upon itself and shaped to provide a reinforcing bead and a box-shaped reinforcing member at said edge, the side edges of said panel being bent rearwardly and inwardly to provide reinforcements for said

edges and channels for receiving guides for a window frame.

8. A sheet metal door comprising a front panel having the top edge thereof bent downwardly and rearwardly to form a box-shaped reinforcing member at said edge, the bottom edge of said panel being bent back upon itself and shaped to provide a reinforcing bead and a box-shaped reinforcing member at said edge, the side edges of said panel being bent rearwardly and inwardly to provide reinforcements for said edges and channels for receiving guides for a window frame, the ends of said top and bottom reinforcing members being secured to the respective ends of said side reinforcing members.

In witness whereof I hereto affix my signature.

EDWARD J. HARDTKE.
